UNITED STATES PATENT OFFICE.

TRACY V. BUCKWALTER, OF ALTOONA, PENNSYLVANIA.

TRUCK.

1,169,768.

Specification of Letters Patent.

Patented Feb. 1, 1916.

Application filed August 18, 1914. Serial No. 857,303.

To all whom it may concern:

Be it known that I, TRACY V. BUCKWALTER, a citizen of the United States, residing at Altoona, in the county of Blair and State of Pennsylvania, have invented 5 certain Improvements in Trucks, of which the following is a specification.

My invention relates to means for pivotally supporting the body of the truck on an 10 axle and my chief object is to provide a simplified and strengthened construction which will eliminate the usual "fifth wheel" with its attending objections.

In the accompanying drawings, Figure 1 15 is a sectional elevation of an end of a truck embodying my improvements; Fig. 2 is a plan view of the same with the floor removed from the frame; Fig. 3 is an enlarged broken front elevation illustrating details of 20 the improvements; and Fig. 4 is a sectional view taken on the line 4—4 of Fig. 3.

The mechanism illustrated in the drawings comprises the traction wheels 1, the axle 2 carried by the wheels, and the frame 3 carried 25 by the axle through the construction hereinafter described. The axle 2 is formed of sections, having convex cylindrical body portions 2^a and conical ends 2^b, provided with registering flanges 2^c connected by rivets 2^d. A post 4 is provided with the foot or shoe 4^a which fits on the top part 2^a of the axle and has the flanges 4^b registering with and riveted to the flanges 2^c. The frame 3 has fixed to its longitudinally interior 30 sills 3^a a transversely extending channel 3^b, the channel having the flanges 3^c riveted to the sills, and through the center of this channel passes the vertical cylindrical bearing 5 having the flange 5^a riveted to the channel, 35 the bearing receiving the journal 4^c at the top of the post 4 and engaging the hub 4^d thereof. A nut 6 is screwed on the journal 4^c into engagement with the bearing 5, where 40 it is held by the key 6^a.

45 The post 4 has a circular channel 4^e forming a journal at its base above the foot 4^a, in which bears the circular foot 7 provided with the struts 7^a which have their top flanges 7^b riveted to the sills 3^a, the foot having 50 the reinforcing collar 7^c riveted thereon. The parts 7, 7^a, and 7^b are conveniently formed by splitting a piece of tubing part way through so as to leave the part 7 an unbroken cylinder, bending the parts 7^a outwardly at the proper angle for providing in-

clined struts adapted to be connected to the sills 3^a at points separated to secure the desired stability, and the parts 7^b so that they will lie flat against vertical surfaces of the sills 3^a. 60

In operation, the load is carried to the axle 2 from the frame 3 through the post 4 by the bearing 5 which engages the hub 4^d and the struts 7^a which act through the parts 7 and 7^c on the bearing 4^e. When the axle 65 2 is turned about the vertical axis of the post 4, the latter's journal 4^c turns in the bearing 5 and its bearing 4^e turns on the parts 7 and 7^c.

Having described my invention, I claim: 70

1. The combination with an axle and a frame having a bearing, of an upwardly tapered tubular post with its base shaped to form a shoe fixed to said axle and its top provided with a journal and hub engaging 75 said bearing to support said frame, said axle and shoe being provided with flanges whereby they are connected, and means for maintaining said frame and post in normal operative relation. 80

2. The combination with an axle and a frame having a bearing, of a post fixed to said axle, said post having a journal at the top thereof for engaging said bearing and a circular peripheral channel thereon providing a bearing adjacent to said axle, a circular foot surrounding said post in engagement with said channel, and struts diverging from said foot and fixed to said frame. 85

3. The combination with an axle and a frame comprising longitudinal sills, of a post fixed on said axle and journaled relatively to said frame, said post having a circular bearing thereon, a circular bearing member surrounding said post in engagement with said bearing first named, and diagonal struts connected to said sills and said bearing second named. 90

4. The combination of a tubular axle and a frame, with a tubular post having a bottom shoe conforming to and fixed on said axle and a peripheral bearing, a circular bearing sleeved on said post in engagement with said bearing first named, and four struts connected with and diverging from said bearing second named to connections with said frame. 100

5. An axle having a convex section with flanges thereon, a post having a foot conforming to said section and flanges engaging 105 110

said flanges first named, and a frame to which said axle is connected in journaled relation by said post.

6. A frame having bearings fixed thereto, an axle having a convex section with flanges thereon, and a post having a foot with flanges fixed to said flanges first named, and bearings connected in journaled relation to said bearings first named.

10. 7. The combination of struts comprising split sections of a tube integrally connected by a tube section forming a bearing, with an axle having a bearing journaled relatively to said bearing first named.

8. The combination of a frame having 15 fixed thereto and converging therefrom struts comprising split sections of a tube integrally connected by a tube section forming a bearing, and an axle having a post provided with a bearing connected in revoluble 20 relation to said bearing first named.

In testimony whereof, I have hereunto set my name this 12th day of August, 1914, in the presence of the subscribing witnesses.

TRACY V. BUCKWALTER.
